UNITED STATES PATENT OFFICE.

HENRY L. PEACOCK, OF DALLAS, TEXAS.

DESIGN FOR AN EARRING.

Application filed April 30, 1923. Serial No. 6,008. Term of patent 3½ years.

To all whom it may concern:

Be it known that I, HENRY L. PEACOCK, a citizen of the United States, residing at Dallas, in the county of Dallas and State of Texas, have invented a new, original, and ornamental Design for an Earring, of which the following is a specification, reference being had to the accompanying drawing, forming part thereof.

Figure 1 is an elevation of an earring, showing my new design,

Figure 2 is another elevation thereof taken at right angles to that shown in Figure 1.

I claim:

The ornamental design for an earring, as shown.

HENRY L. PEACOCK.
